UNITED STATES PATENT OFFICE

WILLIAM A. HOEKSTRA, OF GRAND RAPIDS, MICHIGAN

SWIMMING DEVICE

Application filed March 6, 1930. Serial No. 433,744.

The invention aims to provide a rather simple and inexpensive device with the aid of which persons may propel themselves through the water, simply by operating a pair of hand cranks to drive propellers.

The propellers are disposed within two parallel open-ended cylinders which are strapped or otherwise secured against the swimmer's chest and stomach, and it is a further aim to provide a novel construction and relation of parts in which the cylinders act as supports for a hand-driven drive shaft, and in which gearing connecting said drive shaft with the propeller shafts, is housed totally within the cylinders.

A further aim of the invention is to provide an exceptionally simple and inexpensive cylinder construction which is effectively braced so that the two cylinders remain in fixed relation.

With the foregoing in view, the invention resides in the novel subject matter herein-after described and claimed, description being accomplished by reference to the accompanying drawings.

Fig. 1 is a side elevation showing the device applied.

Fig. 2 is a top plan view.

Fig. 3 is a front elevation.

Fig. 4 is a horizontal sectional view on line 4—4 of Fig. 3.

Fig. 5 is a vertical longitudinal sectional view on line 5—5 of Fig. 3.

The construction shown, may be considered as preferred, with the understanding that within the scope of the invention as claimed, variations may be made.

The numerals 6 denote two parallel longitudinal open-ended cylinders formed by bending a single metal sheet in substantially S shape and securing its ends 7 to its intermediate portion 8, for instance by rivets 9. At its front and rear ends, the portion 8 is provided with openings 10 and 11 respectively, through which front and rear transverse bars 12 and 13 pass, the ends of said bars being secured at 14 to the outer wall portions of the cylinders 6, opposite the portion 8. This anchorage of the bars 12 and 13 may be effected by providing them with reduced

studs passing through openings in the cylinder walls, the studs being either upset or provided with nuts.

The bars 12 and 13 are provided with bearings 15 disposed centrally of the cylinders 6, and two longitudinal propeller shafts 16 are rotatably mounted in these bearings, each of these shafts being provided with two propellers 17 and with a pinion 18.

Between its ends, the portion 8 is formed with a bearing opening 19 and the opposed portions of the two cylinder walls are formed with bearing openings 20, the three openings 19 and 20 being aligned transversely of the cylinders. A drive shaft 21 passes rotatably through the openings 19 and 20 and is provided at its ends with hand cranks 22. This shaft carries two large gears 23 which are confined within the cylinders 6 and mesh with the pinions 18. Rotation of shaft 21 by means of the cranks 22, causes driving of the shafts 16 and their propellers 17, and the gears 23 disposed vertically in the cylinders 6, prevent the water from being violently whirled circumferentially of said cylinders, thus allowing the propellers to act with less slippage than would otherwise take place.

The top portions of the cylinders 6 are tied together by a chest plate 24 secured by rivets or the like thereto, said chest plate projecting forwardly from said cylinders. The lower front portions or other desired portions of the cylinders 6 are tied together by a rudder support 25 upon which an appropriate rudder 26 is mounted. This rudder is provided with a lateral operating arm 27 to which a hand-actuated rod 28 is pivoted, said rod being slidable through a guide 29 carried by the outer side of one of the cylinders 6.

By tying the upper portions of the cylinders 6 together with the chest plate 24 and by tying their lower portions together with the rudder support 25, said cylinders are maintained in rigid relation, even though they be formed by bending a single piece of sheet metal as above described.

The device may be attached to the body in any desired way. Preferably however, I provide the cylinders 6 with a suitable number of loops 30 or the like, through which to

5 pass a waist or body-encircling strap 31. The device is of such size that it may be conveniently carried and operated, and by its use, the swimmer may propel himself rapidly through the water in any desired direction or directions.

10 While the details disclosed may be followed if desired, attention is again invited to the fact that within the scope of the invention as claimed, variations may be made.

I claim:

15 1. In a swimming device, two parallel open-ended cylinders joined to each other at their inner longitudinal sides, a chest plate extending between the top portions of said cylinders and secured thereto, a rudder support extending between and secured to the lower portions of said cylinders, propellers mounted in said cylinders, a rudder mounted 20 on said support, means for driving said propellers, and means for operating said rudder.

25 2. In a swimming device, a pair of parallel cylinders open at both ends and having central bearings at said ends, the sides of said cylinders being also provided with transverse alined bearings between their ends, two longitudinal shafts disposed in said cylinders and rotatably mounted in said central bearings, said shafts being provided with propellers and with pinions all disposed within 30 said cylinders, and a transverse drive shaft passing rotatably through said transverse bearings and having hand cranks at its ends, said drive shaft being provided with two 35 gears within said cylinders respectively and meshing with said pinions.

40 3. In a swimming device, a pair of parallel cylinders open at both ends and having transverse bearings between their ends, a front and a rear transverse bar spanning and secured 45 to the front and rear ends of said cylinders respectively, said bars having bearings disposed centrally of said cylinders, two longitudinal shafts disposed in said cylinders and rotatably mounted in said central bearings, said 50 shafts being provided with propellers and with pinions all disposed within said cylinders, and a transverse drive shaft passing rotatably through said transverse bearings and 55 having hand cranks at its ends, said drive shaft being provided with two gears within said cylinders respectively and meshing with said pinions.

60 4. In a swimming device, a sheet of metal bent into substantially S shape and having its ends secured to its intermediate portion to provide two rigidly joined parallel cylinders, propellers mounted in said cylinders, and driving means for said propellers.

65 5. In a swimming device, a sheet of metal bent into substantially S shape and having its ends secured to its intermediate portion to provide two rigidly joined parallel cylinders, the front and rear ends of said intermediate portion having bar-receiving openings, said

intermediate portions and the opposed portions of the cylinder walls being formed with alined bearing openings between the ends of the cylinders, front and rear bars passing through said bar-receiving openings and secured at their ends to the opposed portions of the cylinder walls, said bars having bearings disposed centrally of the cylinders, longitudinal shafts mounted in said bearings and having propellers and pinions all disposed within 70 said cylinders, and a transverse drive shaft passing through said alined bearing openings and having hand cranks at its ends, said drive shaft having gears within said cylinders meshing with said pinions.

75 In testimony whereof I have hereunto affixed my signature.

WILLIAM A. HOEKSTRA.
